Patented Sept. 26, 1916.

UNITED STATES PATENT OFFICE.

LOUIS H. MEISTER, OF CHICAGO, ILLINOIS.

COLUMN-MOLD.

1,199,095.

Specification of Letters Patent. Patented Sept. 26, 1916.

Application filed March 22, 1915, Serial No. 16,116. Renewed March 10, 1916. Serial No. 88,413.

To all whom it may concern:

Be it known that I, LOUIS H. MEISTER, a citizen of the United States, residing at Chicago, in the county of Cook and State of Illinois, have invented certain new and useful Improvements in Column-Molds, of which the following is a specification.

This invention relates to molds for forming concrete columns and posts, and its object is to provide a novel and improved sectional sheet metal mold of this kind which is adjustable as to height and diameter for columns of different dimensions.

With the herein stated object in view, the invention consists in a combination and arrangement of parts to be hereinafter described and claimed, reference being had to the accompanying drawing in which—

Figure 1 is an elevation of the mold, partly broken away; Fig. 2 is a horizontal section on the line 2—2 of Fig. 1; Fig. 3 is an enlarged sectional detail on the line 3—3 of Fig. 2, and Fig. 4 is an enlarged cross-section on the line 4—4 of Fig. 1.

Referring specifically to the drawing, 10 denotes the wall of the mold, the same being cylindrical in shape and made of sheet metal. The wall is composed of several sections, their number depending on the diameter of the column to be molded. The curvature of the sections is such that when they are assembled they form a true circle. For columns of other cross-sections, the mold wall sections will be shaped accordingly.

35. At the vertical meeting edges of the sections forming the mold wall 10, on the outer face thereof, are secured angle iron strips 11 which are parallel, and so located that their outstanding flanges abut. Through these flanges pass bolts 12, whereby the wall sections are held assembled and prevented from collapsing inward.

The mold wall 10 is externally encircled, at intervals, by hoops 13. The outstanding flanges of the angle strips 11 are notched where the hoops cross the same, the latter seating in the notches. These notches are shown at 14. The inner edges of the hoops, where they cross the flanges of the angle strips which are fastened to the mold wall, have recesses 15 to clear said flanges. The hoops therefore encircle the outside of the mold wall in contact therewith, except at the angle strips 11. The function of the 50 hoops is to firmly hold the mold against bulging outward from the pressure of the

concrete filling the same. The hoops 13 are also made in sections which are pivotally connected by pins 16. The ends of adjacent sections overlap sufficiently to receive a 60 wedge fastening 17 which is driven through alined apertures in said overlapping ends. These wedges firmly hold the sections in encircling position on the mold wall 10, and the notches 14 in the angle strips 11 prevent 65 the hoops from sliding down on said wall. One end of each hoop section has an offset 18, and to said section is welded or otherwise secured, opposite the offset, a tongue 19. The adjacent end of the next section 70 fits between the offset and tongue. The wedge 17 passes through alined apertures in the offset and the tongue and the part therebetween, and the pivot bolt 16 also passes through these parts. By thus doubling the parts through which the pivot bolt 75 and the wedge pass, a better hold is obtained and the wedge is prevented from getting loose.

A number of mold wall units 10 will be 80 employed according to the height of the column to be molded, the units being fastened together in superimposed relation by a ring 20 overlapping the meeting edges thereof and temporarily secured to the units by 85 bolts 21.

Where the upper end of the mold must be flared to form a head for the column, a top section 22 is provided, the same having a flared upper portion 23 carrying a top 90 section 24 slightly overlapping the same. The part 23 carries lugs or ears 25 having vertical slots 26. By means of bolts 27 carried by the part 24 and passing through the slots 26, and wing nuts 28 screwed on 95 said bolts, the part 24 is secured to the part 23.

A mold constructed as hereinbefore described can be easily and quickly set up or taken down, it is strong and durable, and 100 simple in construction, and it effectually serves the purpose for which it is designed.

I claim:

1. A mold comprising an encircling wall composed of sections, strips secured to the 105 outer faces of the sections at the vertical meeting edges thereof, said strips having outstanding flanges, bolts passing through the flanges of adjacent strips, said flanges having notches, hoops encircling the wall 110 and seating in the aforesaid notches, said hoops comprising pivotally connected sec-

tions, and means for locking the sections together.

2. A mold comprising an encircling wall, hoops passing around said walls, said hoops comprising pivotally connected sections offset at one end and having a tongue connected to said end opposite the offset, between which tongue and the offset the end of the adjacent section fits, and a pivot bolt

and a wedge passing through said offset, the tongue and the part therebetween.

In testimony whereof I affix my signature in presence of two witnesses.

LOUIS H. MEISTER.

Witnesses:

MABEL MEISTER,
H. G. BACHELOR.
